UNITED STATES PATENT OFFICE.

THOMAS GEORGE FONNEREAU DOLBY, OF ELGIN, ILLINOIS.

DESIGN FOR A TUB-FASTENING.

SPECIFICATION forming part of Design No. 29,072, dated July 19, 1898.

Application filed November 30, 1896. Serial No. 614,007. Term of patent 14 years.

To all whom it may concern:

Be it known that I, THOMAS GEORGE FONNEREAU DOLBY, a subject of the Queen of Great Britain, residing at Elgin, in the county 5 of Kane and State of Illinois, have invented and produced a new and original Design or Useful Shape for a Tub-Fastening, of which the following, in connection with the accompanying drawings, is a full, clear, and exact 10 specification.

In the said drawings, Figure 1 is a plan view of a tub-fastening embodying my design; and Fig. 2 is a side elevation thereof, partly in longitudinal section.

15 The leading feature of my design consists of a tub-fastening comprising an elongated, narrow, flat, straight strip, thin as compared with its width and having rectangular ends, provided on its upper side with the raised 20 portions A and the button-like circular portions B on top of such raised portions A and on its under side with the point-like projections C at each end.

When the tub-fastening is viewed in side

elevation, as in Fig. 2, the laps A appear as 25 continuations of the main strip or body portion D, whose ends are apparently turned up and folded down against its upper surface; and the enlargements B are circular in plan view, as seen in Fig. 1, and project slightly 30 above the general level of the laps A, whose outer extremities are rectangular. These circular button-like enlargements B are directly over the points or barbs C, and beyond 35 being ornamental they perform a useful function in holding the heads E of the nails or points C. The strip D is also provided adjacent to the laps A with small perforations d.

Having thus described my invention, what I claim as new, and desire to secure by Letters 40 Patent, is—

The new and original design or useful shape for a tub-fastening, substantially as herein shown and described.

THOMAS GEORGE FONNEREAU DOLBY.
